UNITED STATES PATENT OFFICE.

FRANK X. CHASSAING, OF ST. LOUIS, MISSOURI, ASSIGNOR TO SHIRAS-CHASSAING ELECTRIC AND MANUFACTURING COMPANY, OF ST. LOUIS, MISSOURI, A CORPORATION OF MISSOURI.

DESIGN FOR AN ELECTRIC LAMP AND STAND.

46,922.

Specification for Design.

Patented Feb. 9, 1915.

Application filed July 20, 1914. Serial No. 852,070. Term of patent 7 years.

To all whom it may concern:

Be it known that I, FRANK X. CHASSAING, a citizen of the United States, residing at St. Louis, Missouri, have invented a new, original, and ornamental Design for an Electric Lamp and Stand, of which the following is a specification, reference being had to the accompanying drawing, forming a part thereof.

Figure 1 is a side elevational view of an

electric lamp stand embodying my new design. Fig. 2 is a top plan view of the same.

I claim:

The ornamental design for an electric lamp and stand, as shown.

FRANK X. CHASSAING.
